UNITED STATES PATENT OFFICE.

JOSEPH OVILA FORTIN, OF OTTAWA, ONTARIO, CANADA.

DRAFTING MACHINE.

Application filed May 23, 1925, Serial No. 32,364, and in Great Britain June 24, 1924. Renewed October 29, 1926.

This invention relates to drafting machines and more particularly to machines of the class comprising a plurality of connected parallelograms, one of which has a short link attached to the anchoring device and another has a short link carrying the drafting appliance, which is such as a pair of rules secured at right angles, or a protractor. It is the chief object of the present invention to extend the range of usefulness of such instruments, to render them as light and as simple in construction as possible and to enable them to be folded into a small space for transport purposes.

The invention consists in the arrangement and combination of parts to be described hereinafter and more particularly pointed out in the appended claims.

Referring now to the accompanying drawings which illustrate by way of example certain convenient embodiments of the invention,

Fig. 1 is a plan, and Fig. 2 an elevation of the device shown in Figure 1.

Fig. 3 is a plan of a slightly modified parallelogram member.

Fig. 4 is a plan of a modified drafting member.

Fig. 5 is a section through the anchor member joint on line 5—5 of Figure 1.

Fig. 6 is a section through the intermediate joint on line 6—6 of Figure 1.

Fig. 7 is a section through the drafting member joint on line 7—7 of Figure 1.

Fig. 8 is a view of the drafting member plate reversed.

Fig. 9 a plan of a form of plate showing the vernier scale.

Fig. 10 is a plan with one rule and bracket separated, showing the method of securing the rule to the bracket.

Fig. 11 is a side elevation partially in section on line 11—11 of Figure 10.

Fig. 12 is a section on the line XII—XII of Figure 3.

Fig. 13 is an enlarged view of part of Figure 12.

Referring first to Figures 1 and 2, the main part of the machine consists of two jointed parallelogram shaped structures 1 and 2, (hereinafter referred to as parallelograms). The parallelogram 1 comprises a pair of short links 3, 4 and a pair of long links 5.

The parallelogram 2 comprises similar pairs of links 6, 7 and 8. Owing to the improved

method of support, these links are preferably made of metal and nickel plated for finish and may be made considerably lighter than has hitherto been possible. The parallelogram 1 is secured by means of the link 3 to the anchor plate 9, which may be made in the form of a bracket with screw holes 9^a for permanently attaching it to the drawing board or drafting table. The links 4 and 6 are secured together by a clamping screw 10 while the circular plate 11, carrying the drafting attachment is similarly clamped to the link 7 by turning the head 12 of a screw. For cheapness and simplicity all three clamps have their main parts made of the same construction. Figures 5, 6 and 7 show sections through the joints.

In Figure 5 the anchor plate carries a hollow truncated conical or male member, which is engaged by a hollow truncated conical or female member 14. These are drawn together by a clamping screw 15 which forms an extension of a pillar 16, to be referred to later. The shank end of the screw 15 makes a good fit through plane holes in the link 3, and the clamp member 14. By loosening the clamping screw 15, the link 3 may be adjusted easily into any required angular position, relative to the anchor plate 9.

Similarly in Figure 6 the intermediate joint comprises a male member 17 carried on link 6, a female member 18, carried on link 4, and a clamping screw 19, formed with a large head 10; while the drafting joint, Fig. 7, comprises a male member 20 carried by the circular plate 11, a female member 21, carried by the link 7, and a clamping screw 22, over which fits an internally threaded tubular nut 23, having an enlarged head, 12.

In each case by this method of construction, the clamping members are of such a size that the top surface of the male member does not reach the inner flat surface of the hollow member. The fitting of the joints thus depends only on the conical sides of the members, which can be made very accurately.

It will be seen that the members secured together at each of the three joints are thus easily angularly adjustable relatively to each other, and turn truly about the centre point.

Referring now particularly to Figures 1, 7, 10 and 11, the drafting appliance comprises a supporting plate 25, having the bracket arms 26 rigidly secured to it by means of a bar 27. The graduated circular

plate 11, previously referred to, may rotate on the supporting plate 25, or may be clamped thereto by means of a clamping screw 28. The bar 27 also carries a segment 29, which may bear a zero mark, as shown in Figure 1, or may have a vernier scale as shown in Figure 9. In order to fix the zero mark accurately at certain common angles, for example 30° , 45° and 60° , holes 30 (see Fig. 8) are made in the supporting plate 25. In addition to the examples given above a hole is made (though it is not shown in the drawings) at 0° . The graduated plate 11 carries a plunger 31 (see Fig. 7) fitting the holes accurately, which is normally maintained out of contact with the supporting plate 25 by a spring 32 inside a cap 33. When it is desired to draw lines at say 30° to the zero line, the supporting plate 25 is rotated relatively to the plate 11, and simultaneously the cap 33 is pressed downwards. When the bracket is at 30° to its initial position, the plunger will sink into the hole 30, when the screw 28 may be clamped and apparatus fixed.

It is found with some sizes of machines that if the circular plate 11 has its pivot exactly half way along the link 7, this link and the rods 8 are apt to obscure the scale. In order to avoid this it is preferable to secure the clamp nearer to one end of the link 7 than the other, as is shown in Figure 1.

The means for supporting the intermediate joint and for preventing it from sagging when it is off the board, are shown in Figures 2, 5 and 6, and comprise the pillar 16, and a thin circular tie rod 34. The lower end of this tie rod is formed with a ring 35, which engages with the reduced or neck portion of an upstanding stud on the top of the clamp 19 at the intermediate joint. The tie rod 34 is made slightly longer than is necessary and the upper end is screwthreaded. An inverted cup 36, which engages the head of the pillar 16, fits over this screw-threaded portion and is held in position between two nuts 37; by adjusting these, the intermediate joint can be held at any desired distance above the drawing paper.

In order to prevent the tie rod 34 pulling some of the joints between the links apart, these latter are formed by means of upstanding pins 38 (Figure 5), which fit accurately within holes in the members with which they make joint. These pins have upper reduced ends, and are furnished with milled nuts 39 to prevent the joints coming apart.

Referring now to Figs. 10 and 11 the supporting bracket for the rules is formed with a pair of arms 26, extending at right angles. These are designed to fit over the rules 40 which are provided with metal plates 41, having two hemispherical projections or studs 42, 43. These studs fit into corresponding depressions 44, 45 in the bracket arms.

The depression 44 is made in the shape of a hemispherical hole, fitting the stud 42 accurately while the depression 45 is made as a groove, semi-circular in cross section. This connection ensures accurate location of the rule by means of the stud 42 and hole 44 and allows, by means of the groove 45, for slight variations in distance between the studs 42 and 43. The rules and bracket arms are drawn together and clamped by means of screws 46 passing through holes 47 in the bracket arms and screwing into tapped holes in the plates on the rules.

In order to avoid distortion of the rules during clamping, the depression 44 is made slightly less than a hemisphere and the depression 45 is slightly less than a semicircle in cross section throughout its length. This allows of a slight rocking of the rule relative to the plate and as the holes 47 in the bracket arm are made larger than is necessary, the rule can be clamped either parallel with the bracket arm or else inclined at a small angle thereto. This allows the rules always to be set in the same plane as the surface of the drafting table. The metal plates 41 are secured to the rules 40 in the following way: At one end of each plate there is a screw 42 passing into the wood of the rule. The head of this screw forms one of the hemispherical studs; at the other end a second screw 49 passing through a slot 50 cut in the plate 41, which screw and slot lie beyond the bracket arm 26. By loosening the screw 49, slight angular adjustment of the rule relative to the plate can be made, the screw 42 acting as a hinge. The second hemispherical stud 43 has a shank which does not pass into the wood and therefore does not interfere with this adjustment. Both the rules 40 are provided with two metal plates 41, one at each end, so that the rules are reversible. This is of great convenience as a metric scale can be used on one edge, and an inch scale on the other. With the construction described there is no difficulty in reversing the rules, all that is needed being to loosen the screws 46. Rules secured in this way are accurately located, and there are no large projecting parts to interfere with the draftsman's work.

Although one particular machine has been described, considerable variations may be made without departing from the scope of the invention. For example, the metal bracket arms 26 may be formed as partial tubes, each having a section slightly less than a semi-circle, instead of having two hemispherical depressions to receive the studs on the plates. Again, only one screw 46 may be used to clamp the rule to the bracket.

In yet another variation, the means for engaging the tie rod with intermediate joint may comprise, in place of the ring 35, an in-

verted cup engaging with a correspondingly shaped undercut recess in the clamp.

In Figure 4 the drafting member comprises a substantially U-shaped plate 67 which is pivoted to the short link 7 and can be clamped thereto by means of a pair of co-acting cone members 21 and 68 similar to those already described. One limb of the plate 67 has a rule detachably connected directly to it and the other limb has pivoted to it at 71 a graduated sector 70 which detachably carries a rule and may be clamped in adjusted position by means of a clamping screw 73 which is arranged to press a small plate 74 into frictional engagement with a flange on the plate 70.

Figures 3 and 12 are respectively plan and partial section of an attachment suitable for use by a surveyor. In this form 20 a plate 53 is pivotally attached to link 7 by means of co-acting cone members 51 and 51' which may be clamped by a screw 52, the plate 53 being secured to cone 51 by screws 54. The plate 53 is approximately 25 triangular and a graduated ring 55 is attached to it by means of screws 56. The ring 55 is supported in horizontal position as by means of feet 57. A flange on an annular graduated plate 58 lies in a recess in 30 the inside of plate 55 and may be clamped to plate 55 by means of a nut and bolt 60, the bolt having a flange engaging the underside of ring 55 and keyed to ring 58 by a pin 62. Two elbows 63 are carried by the 35 ring 58 and a graduated rule 64 is attached to the elbows by means of screws 65, engaging slots in the brackets which permits adjustment of the rule.

It will be understood that various changes 40 may be made in the details of the construction and in the drafting attachments without departing from the scope of the invention as defined in the appended claims. For example, any number of parallelogram structures may be connected together as may 45 be necessary to move the drafting attachment to the position where the drawing work is to be done.

What I claim is:

50 1. A drafting machine comprising, in combination, a pair of pivotally connected parallelogram-shaped structures each consisting of a pair of parallel short links pivotally connected by a pair of parallel longer links, an anchoring device pivoted to the short link at one end of the machine, and a drafting member carried by the short link at the other end of the machine, said drafting member comprising a pair of rules, a 55 bar pivoted to the last mentioned short link and carrying one of the rules and a graduated member pivoted on the bar and carrying the other rule.

60 2. A drafting machine comprising, in combination, a pair of pivotally connected

parallelogram-shaped structures each consisting of a pair of parallel short links pivotally connected by a pair of parallel longer links, an anchoring device pivoted to the short link at one end of the machine and a 70 drafting member carried by the short link at the other end of the machine, said drafting member comprising a bar pivoted to the last mentioned short link and having two 75 arms, a rule detachably carried by one of the arms, a graduated member pivoted to the other of the arms and detachably carrying a second rule and means for clamping said graduated member in adjusted position. 80

3. A drafting machine, as defined in claim 2, wherein the rules are provided with plates for the purpose of securing them to the arm and graduated member, said plates having substantially hemispherical studs adapted to fit into corresponding holes in the said arm and member respectively, to which they are attached, and screws for clamping said rules in adjusted position. 85

4. A drafting machine, as defined in claim 90 2, wherein the rules are provided with plates for the purpose of securing them to the arm and graduated member, said plates having substantially hemispherical studs adapted to fit into corresponding holes in the said arm 95 and member respectively, to which they are attached, and screws for clamping said rules in adjusted position, said holes being formed substantially as a hemispherical recess and as a groove of semi-circular cross section respectively, so that accurate fitting may be obtained even when the distance between the studs varies substantially as described. 100

5. A drafting machine, as defined in claim 105 2, wherein the rules are provided with plates for the purpose of securing them to the arm and graduated member, said plates having substantially hemispherical studs adapted to fit into corresponding holes in the said members, to which they are attached, and screws for clamping said rules in adjusted 110 position, said holes being formed substantially as a hemispherical recess and as a groove of semi-circular cross section respectively, so that accurate fitting may be obtained even when the distance between the studs varies, wherein provision is made for 115 rocking the rules relative to their respective carrying members by making the said holes in the latter slightly less than hemispheres or than half cylinders, respectively, and by making holes which receive the screws in the said carrying members of greater diameter than the said screws, as 120 herein described. 125

6. A drafting machine, as defined in claim 130 2, wherein the rules are provided with plates for the purpose of securing them to the arm and graduated member, said plates having substantially hemispherical studs adapted to

fit into corresponding holes in the said members, to which they are attached, and screws for clamping said rules in adjusted position, and wherein each rule has two similar plates, one at each end, and is thereby made reversible.

7. A drafting machine, as defined in claim 1, having a graduated disc on said bar and capable of rotation with respect thereto, an index device coacting with the graduations

on the disc and carried by the bar, means for clamping the disc to the link, means for clamping the bar to the disc, a plunger carried by the disc and a plate between said disc and bar, fixed to the bar and having a hole adapted to be engaged by said plunger when the latter is depressed.

In testimony whereof I affix my signature.

JOSEPH OVILA FORTIN.
